UNITED STATES PATENT OFFICE.

SERN MADSEN, OF CLINTON, IOWA, ASSIGNOR TO CURTIS COMPANIES, INCORPORATED, OF CLINTON, IOWA.

FEEDING MACHINE.

Application filed April 23, 1924. Serial No. 708,483.

My invention relates to a feeding machine for door stickers and the like.

The purpose of my invention is to provide a feeding machine, which will be used between two wood working machines, such for instance as a double-end tenoning machine and a door sticking machine, and will function for taking the stock from the tenoning machine and feeding it to the sticking machine.

The object of my invention is to provide such a feeding machine, having parts so constructed and arranged as to be adjusted for receiving and handling stock of different lengths, thicknesses and widths.

A further object is to provide such a machine, whereby stock may be fed to either of the two sets of cutter heads in a sticking machine.

Another object is to provide in the feeding machine, mechanism for handling stock, so that if two pieces of stock are fed to the feeding machine at once, they will be separated and fed one at a time to the sticking machine.

With these and other objects in view, my invention consists in the construction, arrangement and combination of the various parts of my feeding machine, whereby the objects contemplated are attained, as herein-after more fully set forth, pointed out in my claims, and illustrated in the accompanying drawings, in which:

Figure 1 shows a top plan view of a feeding machine embodying my invention.

Figure 2 shows a plan view of the rear or receiving end of the machine.

Figure 3 shows a rear elevation of the machine.

Figure 4 is a detail, sectional view taken on the line 4—4 of Figure 3.

Figure 5 is a transverse, sectional view taken on the line 5—5 of Figure 4.

Figure 6 is a detail view of part of the stock handling mechanism.

Figure 7 is a detail, sectional view taken on the line 7—7 of Figure 1.

Figure 8 is a detail, sectional view taken on the line 8—8 of Figure 7.

Figure 9 is a detail, side elevation of part of the mechanism for feeding the stock from the feeding machine to the sticking machine.

Figure 10 shows a detail, sectional view

taken on the line 10—10 of Figure 9, illustrating part of the mechanism for feeding the stock from the feeding machine to the sticking machine; and

Figure 11 shows a detail, side elevation of part of the mechanism for the receiving end of the device, the view being taken from the opposite side of the machine, as shown in Figure 3.

In a general way, it may be said that this machine is adapted to receive stock from a tenoning machine and to carry it on carrier bars by means of chains arranged above the carrier bars up said carrier bars, which are inclined. The stock is then discharged from the carrier bars upon a pentagonal drum or reel. This reel is geared to rotate in either direction for discharging into either of the two troughs located on opposite sides of the reel.

In the bottom of the troughs are conveyor chains arranged to travel at substantially right angles to the direction of the travel of the stock up the carrier bars. The stock is fed from the chains in the troughs by feed rollers to the sticking machine.

Mechanism for receiving the stock from the tenoning machine and advancing it to the reel.

The feeding machine of the present invention is designed to be connected with a tenoning machine of the type used in tenoning the ends of door frame members.

In the accompanying drawings, I have used the reference numeral 10 to indicate generally the frame of the tenoning machine.

Mounted on the forward end of the tenoning machine is a transverse shaft 11 on which are sprocket wheels 12 for the chains 13 of the tenoning machine.

It may be said in this connection that one of the chains of the tenoning machine, indicated at B in Figure 2, is arranged to be laterally adjustable in the manner not here particularly referred to, because the tenoning machine in itself forms no part of my present invention.

The tenoning machine has laterally adjusted frame parts 14. The feeding machine has a frame 15, shown for instance in Figure 3, which is designed and used to be spaced from the frame 10 of the tenoning machine. The frame 15 has upwardly ex-

tending brackets 16 in which a shaft 17 is journalized.

The portion of the feeding machine now being described, which receives the stock

5 from the tenoning machine consists in a general way of a pair of bars inclined upwardly and away from the tenoning machine. The stock is designed to be slid upwardly on these bars. One of the bars is laterally adjustable for accommodating the feeding machine to stock of different lengths.

The stock is carried up the bars by a pair of chains arranged above the bars and provided with downwardly projecting fingers 15 for engaging the stock.

On the fixed frame 10 of the tenoning machine is a bracket 18, shown in Figure 3, which has a bearing for the shaft 11 heretofore referred to. This bracket has a forwardly extending arm 19 provided with a horizontally elongated slot 20, shown in Figure 3.

A casting 21, shown in Figure 3, has fixed thereto a laterally projecting spindle 22, for 25 one of the sprockets 23 for one of the stock advancing chains of the feeding machine.

The casting 21 is fixed to an angle iron 24 inclined upwardly toward the shaft 17 and having at its upper end a journal 25 for the 30 shaft 17. The angle bar 24 constitutes a radius rod, for maintaining the distance between the centers of the sprockets on which travel the left-hand chain of the stock advancing means of the feeding machine.

35 On the shaft 17 in line with the sprocket 23 is a sprocket 26. A chain 27 travels on the sprockets 23 and 26. Spaced from the chain 27 is a similar chain 28. On the shaft 17 is a sprocket 29 similar to the sprocket 26, excepting that it has a grooved hub 30, which is slidably but non-rotatably mounted on the shaft 17.

A two-part bearing or journal member 31 is mounted on the hub 30 to permit free rotation of said hub.

50 A radius rod angle iron 24^a is connected with the bearing 31 and extends rearwardly parallel with the angle iron bar 24. At its rear end, the bar 24^a is connected with a casting 21^a, similar to the casting 21 in the same manner that the bar 24 is connected with the casting 21. The casting 21^a supports a spindle 22^a on which is a sprocket 23^a laterally opposite the sprocket 23 and 55 aligned with the sprocket 29. The castings 21 and 21^a have vertical slots 21^c. Bolts 21^d are extended through the slots 21^c and 32^a, referred to below, for supporting the castings 21 and 21^a on the brackets 18 and 31^a.

60 The chain 28 travels on the sprockets 29 and 23^a. The bracket 21^a is supported on a bracket 31^a having a horizontally elongated slot 32^a, similar to the slot 20 in the same way that the bracket 21 is supported on the bracket 18. The bracket 31 is connected with

one member of an A-shaped frame 32, the rear ends of which are supported on the laterally movable frame member 14 of the tenoning machine.

The carrier bars 33 are pivotally supported at their rear ends on projecting frame members 34 and 35. (See Figures 1, 2 and 3.) The member 34 is connected with the fixed frame of the tenoning machine and the bracket or member 35 with the laterally movable portion of the tenoning machine.

On each side of the frame 15 is a trough 36 extending generally and substantially at right angles to the carrier bars 33, as shown for instance in Figure 3.

These troughs will be hereinafter more fully explained.

Upon the wall 36^b of the right-hand trough 36 are supports 37. A vertical, adjustable cross bar 38, shown in Figures 3 and 4, has parallel inclined slots 39. Bolts 40 are extended through the slots 39 and are mounted on the supports 37.

Supported on the wall of the trough 36, which supports the members 37 is an angle iron 41. A rod 42 is pivoted to the bar 38 and is slidably extended through the flange 41^a of the angle iron 41 and has its outer end screw-threaded to receive the nut 43, having the handle 44, as shown in Figure 4.

By adjusting the nut 43, the bar 38 can be adjusted for vertically adjusting the forward ends of the carrier bars 33.

For snugly holding the carrier bars downwardly against the adjustable bar 38, I have provided the following means:

Brackets 45 extend downwardly from the respective radius rod angle bars 24 and 24^a and have at their lower ends feet or extensions 45^a, extending toward each other.

65 Bolts 46 secured to the carrier bars 33 are extended through the extensions 45^a and project downwardly below said projections substantial distances.

On the bolts 46 between the heads thereof and the extensions 45^a are coil springs 47, which tend to pull the carrier bars 33 downwardly against the bar 38.

The extensions 45^a are usually not in contact with the bars 33, but stand slightly below such bars.

For operating the carrier chains 27 and 28, the following means are provided:

A yoke 47^a has bearings 48 mounted on the shaft 11 of the tenoning machine. The yoke 47^a has a bearing 49 for one end of a two-part shaft 50. The two parts of the shaft 50 are connected with a sleeve 51. The sleeve 51 is fixed to one member of the shaft 50 and is secured to the other member by means of a shearable pin 52. This connection forms a safety device.

The upper end of the shaft 50 is mounted in a bearing 53 formed on a yoke 54. The yoke 54 has its arms provided with jour-

nals 55 through which the shaft 17 extends.

On the shaft 11 is a beveled gear 56 in mesh with a beveled gear 57 on the shaft 50. On the shaft 17 is a beveled gear 58, which meshes with a beveled gear 59 on the shaft 50 for this transmitting power from the shaft 11 to the shaft 17.

In the operation of the portion of the feeding machine above-described, power is transmitted from the shaft 11 to the shaft 17, through the beveled gears 56 and 57, the shaft 50 and the beveled gears 59 and 58. The rotation of the shaft 17 operates the sprockets 26 and 29 and the chains 27 and 28. The chains 27 and 28 have projecting fingers or lugs 60, which travel above the level of the carrier bars 33.

Stock is fed to the carrier bars 33 from the tenoning machine and is then engaged by the fingers 60 and carried up the carrier bars 33 to the other part of the feeding machine.

It will be understood that the size of the sprockets, the arrangement of the fingers 60, and the arrangement of the gears for operating the sprockets 26 and 29 are such that the chains 27 and 28 are synchronized with the chains of the tenoning machine or other means, whereby stock is fed to the carrier bars 33.

The lower ends of the chains may be readily adjusted vertically by loosening the nuts on the bolts 21^a and raising or lowering the castings 21 and 21^a.

Similarly, the upper ends of the carrier bar 33 may be vertically adjusted by operating the handle 44 on the nut 43, for sliding the bar 38 longitudinally.

By these adjustments of the chains 27 and 28 and the carrier bars 33, the distance between the lower stretches of the chains and the carrier bars may be varied for accommodating the feeding machine for stock of different thicknesses.

The adjustment may be such as to make the chains inoperative, so that stock may be removed from the lower ends of the carrier bars without being operated upon by the chains 27 and 28.

This is sometimes desirable where the tenoning machine and the feeding machine are connected, but it is not desired to feed the stock through the feeding machine.

It will be seen that the lateral adjustment of the laterally movable portion of the tenoning machine carries with it the A frame 32 and the sprocket 29 and the bracket 35 for thus laterally adjusting the chain 28 and the right carrier bar 33. This adjustment is necessary for handling stock of different lengths.

The feeding reel.

Mounted between the troughs 36 above referred to is what I may call the reel or drum for handling stock.

A shaft 62 is mounted on the frame 15 of the feeding machine and extends longitudinally thereof between the troughs.

Mounted on the shaft 62 is a series of equi-distantly spaced reel members, comprising the pentagonal spider elements 64. The reel thus formed is rotated in either direction for discharging stock into either of the troughs 36 as may be desired.

The means for rotating the reel includes a pair of sprockets 66 and 67, shown in Figures 1 and 4 fixed on the shaft 17. On the shaft 62 in line with the sprocket 66 is a sprocket 68 and on the shaft 62 in line with the sprocket 67 is a sprocket 69.

A chain 70 travels on the sprockets 67 and 69 for transmitting rotation from the shaft 17 to the sprocket 69. An idler sprocket 71 is mounted on the frame 15 in line with the sprockets 66 and 68. A chain 72 travels on the sprockets 66 and 71 and has one stretch engaged with the right-hand face or portion of the sprocket 68.

It will thus be seen that the sprockets 68 and 69 are operated in opposite directions. These sprockets 68 and 69 are rotatably but non-slidably mounted on the shaft 62.

Selectively, operatively connecting either the sprocket 69 or the sprocket 68 with the shaft 62, there is splined in the usual way on the shaft 62, a double-faced clutch 73, having a central annular groove 74. (See Figures 1, 4 and 7.)

The hubs of the sprockets 68 and 69 have clutch faces 75 for coacting with the clutch 73.

A clutch shifting lever 76 is pivoted to a bracket 77 on the frame 15, as shown in Figure 4, and is provided with a yoke 78 (see Figure 1) of ordinary construction for coacting with the groove 74 of the clutch 73.

By shifting the lever 76, the clutch 73 may be adjusted for operatively connecting either of the sprockets 68 or 69 with the clutch and with the shaft 62 for thus operating the shaft 62 in either direction from the shaft 17.

It will be understood that the gearing connections for the reel are such as to cause the flat surface of the reel to be presented for receiving stock discharged from the carrier bars 33 by the movement of the chains 27 and 28.

As the reel revolves, it discharges the stock carried upon its upper flat surface into one or the other of the troughs 36 depending upon the direction of rotation of the reel.

Chains 79 travel in the bottom of the troughs 36 and are operated by the means hereinafter more fully referred to.

At this time, I desire to call attention to a feature of this machine, which enables it to do speedier work than would otherwise be possible.

Sometimes two narrow pieces of stock are fed through the tenoning machine adjacent to each other and are discharged upon the carrier bars 33 substantially at the same time.

5 Two pieces of stock would thus be carried up the carrier bars together and discharged together upon one flat face of the reel.

Two pieces should not be carried at once upon the same chains 79, because two pieces 10 can not be simultaneously fed to the sticking machine.

I have therefore provided the following means for separating two such pieces as they are discharged into the trough 36, one above 15 the other on edge.

The inner walls of the troughs 36, as shown at 36^a, terminate at their upper edges considerably below the upper edges of the outer walls 36^b. About level with the bottoms 36^c of the respective troughs and near the troughs are shafts 80 extending through the machine lengthwise parallel with the reel. These shafts 80 are mounted for rotation.

25 Supported on the shafts 80 are a series of selector fingers 81, which at their upper ends have curved portions projecting laterally, as shown at 81^a, for instance in Figure 5.

30 The fingers 81 are arranged in opposite pairs between the successive spiders 64 of the reel. Arms 81^b project below the shafts 80 and are connected by a coil spring 82.

Pivoted connected to the lever 76 is a rod 35 83 extending toward the discharge end of the machine.

Near the discharge end of the machine are two cam discs 84 spaced from each other and fixed to the shaft 62 by set screws 85. 40 On the adjacent faces of the discs 84 are mounted rollers 86.

On the shafts 80 between the discs 84 are slidably but non-rotatably mounted sleeves 87. On the rod 83 are mounted laterally extending arms 88. The arms 88 have rotatable connection with the sleeves 87 and are designed to slide said sleeves on the shafts 80 when the rod 83 is moved longitudinally.

The rod 83 is connected with the lever 76 50 by means of a link 89, which link is pivoted to the lever 76 and is also pivoted to the rod 83. The rod 83 slides in bearings 90 in the frame 15.

Projected inwardly or upwardly from the 55 sleeves 87 between the discs 86 are cam arms, comprising in each instance a channel-shaped arm 91, having pivoted to the side thereof, as at 92, a cam arm 93. The cam arms 93 are thus mounted on the channel-shaped arms 91 for lateral pivotal swinging movement.

For holding the cam arm 93 against pivotal movement between the flanges of the channel arm 91 is a bolt 94 secured to the arm

91. This bolt is extended through a hole 65 shown at 96 in dotted lines in Figure 6, which hole is large enough to allow sufficient play of the parts.

Between the head of the bolt and the cam arm 93 is a coil spring 97.

For pressing the right-hand or left-hand series of selector fingers 81 inwardly and holding them in inoperative position, I provide rods 98 mounted in the frame 15 and extending alongside the troughs 36 and the 75 inside thereof at the outer ends of the rods 98 are handles 99, shown in Figure 3.

On the rods 98 adjacent to one selector finger 81 on each shaft 80 is a cam 100, so arranged that when a rod 98 is rotated to 80 a certain position, the cams will engage the fingers and force them inwardly to inoperative position.

Normally the spring 82 tends to hold the curved portions 81^a of the selector fingers 85 81 to position overhanging the inner wall of the adjacent trough 36, as shown at the right-hand side of Figure 5.

In Figure 5, the rod 98 at the left-hand side of the figure is shown rotated to its 90 position where the cams 100 hold the left-hand series of fingers 81 in inoperative position.

I will now describe briefly the operation of the reel.

Assuming that the stock is being carried up the carrier bars 33 to the reel, then the lever 76 is manipulated for operatively connecting the clutch 73 with the sprocket 69 or the sprocket 68, as the case may be, for 100 rotating the reel in the direction desired to discharge stock into the proper trough 36.

When it is desired to discharge the stock into the other trough, the lever 76 is shifted for connecting the clutch with the other 105 sprocket 68 or 69.

If the stock is being carried to the reel, one piece at a time, it is unnecessary to use the selector fingers 81, and they may be rendered inoperative by rotating the rods 110 98, for causing the cams 100 to hold the fingers 81 pressed inwardly.

If it happens that two pieces of relatively narrow stock are being carried up the carrier bars 33 with their adjacent edges together, and it is desired to separate them, when they are discharged from the reel, then the rod 98 adjacent to the trough receiving the stock is moved to position with the cams 100 on that rod standing as shown 120 in Figure 5.

The parts are so arranged that when the reel is discharging into the right-hand trough, as shown in Figure 5, the right-hand cam arm 93 will be adjacent to the 125 rearward cam disc 84, to-wit, the one nearest the discharge end of the machine.

If the fingers 81 are being held in inop-

erative position, the rollers on the disc 84 may rock the cam arm slightly, but will have no further effect.

If, however, as has been stated, it is desired that the right-hand series of selector fingers be operated, then the rollers will engage the right-hand cam arm 93 at proper times synchronously with the other operations of the machine for swinging the right-hand fingers 81 inwardly, when the stock is discharged from the reel into the right-hand trough 36, and will permit them to swing quickly outwardly on account of the action of the spring 82 in time to catch the upper member of the two pieces of stock 101, as shown in Figure 5.

The lower piece of stock will then be carried along the trough by the chain 79 and when the next roller engages the cam arm 93, the fingers 81 will be swung inwardly again for releasing the upper piece of stock 101 and dropping it to the bottom of the trough.

This occurs long enough before the next piece of stock is dropped into the trough to permit the last-mentioned piece of stock to be carried out of the way by the chains 79.

It should perhaps be noticed that the ends of the cam arms, which contact with the rollers on the cam discs 84 are so shaped as to give a quick release of the fingers, after they have been held by the cam arms in their open or inoperative position, so that they are permitted to move outwardly quickly in response to the action of the springs 82.

It will, of course, be understood that the cam on the arm 93 is of just the proper shape and that the length of the arm is just sufficient to accomplish the purposes mentioned.

The mechanism for the release of the fingers can be timed accurately by adjusting the cam discs on the shaft 62 by means of the set screws 85.

It should be mentioned too that in event the lever for reversing the reel should be moved while the reel is in stationary position and it should happen that the cam arm 93 should engage one of the rollers instead of entering the space between two successive rollers, the cam arm will not be bent, but will be swung on its pivot 92, until the reel is started, whereupon the spring 97 will return the cam arm to its normal position.

Discharge and feed rollers.

I will now describe the rollers which feed the stock from the troughs to the sticking machine or from the feeding machine, and in connection therewith will refer to the operating mechanism of the chains 79 in the troughs.

The feed rollers and the chains in the

troughs 36 are driven from the motor 102, shown in Figure 4. On the motor shaft 103 is a belt pulley 104, in line with a belt pulley 105 on the power shaft 106. A belt 107 travels on the pulleys 104 and 105. On the shaft 106 is a belt pulley 107^a in line with a pulley 108 on the shaft 109. A belt 110 travels on the pulleys 107^a and 108.

Mounted at the rear ends of the troughs 36 are sprockets 111 over which the chains 79 travel.

Spaced rearwardly from the front ends of the troughs 36 just below the troughs is a transverse shaft 112 on which are sprockets 113, which project upwardly through holes 114 in the bottoms 36^c of the respective troughs 36. (See Figs. 1 and 4.)

The chains 79 travel over the sprockets 113, their upper stretches traveling on the bottoms 36^c.

On the shaft 112 is a sprocket 115 arranged in alignment with a sprocket 116 on the shaft 109.

Arranged forwardly with relation to the shaft 112 and below the troughs 36, a shaft 117 is mounted in bearings 118.

On the shaft 117 is a sprocket 119 aligned with the sprockets 116 and 113. A chain 120 travels on the sprockets 116, 113 and 119.

It will be seen that the chains 79 are operated from the sprockets 113 on the shaft 112. The motor 102 through the belt pulley 107 operates the belt pulley 105 and the shaft 106. The shaft 106 transmits rotation through the belt 110 to the pulley 108 and the shaft 109. The shaft 109 through the sprockets 116 and 115 (Figures 1 and 4) operates the shaft 112 for thereby rotating the sprockets 113.

For feeding the stock from the forward ends of the troughs, which do not have the chains 79, I provide feed rollers, the construction and operation of which will now be described.

Near the front or discharge ends of the troughs 36, there are mounted in suitable bearings 121 and 122, shafts 123, which are inclined slightly forwardly from the vertical, so as to hold the stock securely against the bottom of the trough, and thus feed it into the sticking machine in proper relation to the bed of the sticking machine.

At the upper ends of the shafts 123 are feed rollers 124, which project through openings 125 in the inner walls of the troughs 36 a sufficient distance to engage stock traveling along those troughs.

In the lower portions of the shafts 123 are beveled gears 126, which mesh with beveled gears 127 on the shaft 117. Mounted in suitable bearings 128 spaced laterally from the bearings 122 are short upright shafts 129, connected by universal joints

130 with upwardly projecting and forwardly inclined shafts 131.

Connected with the upper ends of the shafts 131 by universal joints 132 are short shafts 133 on which are rollers 134, which also project through holes 135 into the troughs 36.

For pressing the rollers 134 inwardly yieldingly for thus causing the rollers to engage stock of different thicknesses, the upper end of each shaft 133 is journaled in one end of a pivoted bearing arm 138. The arms 138 are pivoted to brackets 139 on the side walls of the troughs 36.

Projecting outwardly from such side walls are bolts or the like 140, which slidably extend through the arms 138 and have coil springs 141 between the nuts 142 thereon and the arms 138 for yieldingly pressing the arms 138 inwardly.

Bolts 143 are mounted in the walls of the troughs 36 and loosely extended through the arms 138 for further adjusting them.

On the lower ends of the shafts 123 are spur gears 144 meshing with spur gears 145 on the lower ends of the shafts 129 for thus transmitting motion from the shafts 123 to the shafts 129.

It will be noted that there are two feed rollers for each trough and that the outer one of each pair of rollers is yieldingly pressed inwardly. The rollers are also inclined slightly from the horizontal, so as to press the stock downwardly and properly feed it to the sticking machine.

Operation.

I will now describe the operation of the entire feeding machine.

Stock is fed from the tenoning machine to the inclined carrier bars 33. The fingers 60 on the chains 27 and 28, which are synchronized with relation to the chains of the tenoning machine, engage the successive pieces of stock and slide them up the bars 33 at the upper ends thereof and discharge the stock upon the flat surfaces of the spider 64 of the reel.

Lateral adjustment of the adjustable portion of the tenoning machine carries with it the A-shaped frame 32, the chain 28 and the right-hand carrier bar 33 for adjusting the feeding machine for stock of different lengths.

The reel, being so timed as to receive the stock upon one of its flat faces, as fed by the fingers 60, will then rotate either to the right or left, depending upon the adjustment of the lever 76 and the clutch 73 into one of the troughs 36.

The chains 79 then carry the stock along the trough to the discharge end thereof.

If it occurs that two pieces of narrow stock are being fed to the carrier bars at one time, then the handle 99 is adjusted for

rotating the rod 98 of the trough, which is receiving the stock, and rendering the cams 100 inoperative.

The adjustment of the lever 76 for causing the reel to operate to discharge into one or the other of the troughs serves through the rod 83 and the arms 88 to adjust one or the other of the cam arms 93 to position to be engaged by the rollers 86 of one of the cam discs 84.

The parts are so timed that a roller 86 will engage the cam arm for rocking the shaft 80 and moving the selector fingers 81 to inoperative position, when the stock is discharged from the reel.

The rollers 86, however, clear the cam arms 83 at such times as to permit the springs 82 to swing the operative selector fingers 81 outwardly to cause the portions 81^a thereof to engage the uppermost of the two pieces of stock 101, as shown at the right-hand side of Figure 5. The lowermost piece of stock is then carried away by the chains 79, and thereafter the selector fingers are operated to release the stock held by them, which then drops upon the chains 79 and is carried toward the discharge end of the machine.

The stock when carried to the discharge end of the machine is engaged by the pair of rollers 124 and 134 and fed from the troughs 36 to the sticking machine.

My feeding machine has a number of advantages.

It provides for the automatic feeding of stock from one wood-working machine to another without the necessity for manual handling and particularly without the necessity of manual feeding to the sticking machine.

The feeding machine is readily adjusted for receiving and handling stock of different lengths or thicknesses. It can be adjusted so that stock may be fed upon the carrier bars, and the feeding machine will then be inoperative, so that the stock can be taken from the carrier bars without being operated upon by the feeding machine.

The feeding machine is readily adjustable for feeding the stock to either of two different sets of the cutter heads on the sticking machine, so as to quickly feed stock to one or the other of these sets of heads without any delay in changing heads.

The feeding machine is provided with means whereby it is capable of handling two pieces of narrow stock received at one time from a tenoning machine and feeding such stock one piece at a time to a sticking machine.

This feeder permits the operation of either the sticker or tenoner independently of the other. This is a great advantage in case of breakdown of one machine. The sticker may be fed directly through the troughs of

the feeder, or the stock may be removed from the tenoner either just as it starts up the conveyor bars or just as it is delivered on the reel. This also permits operating the two machines independently on different kinds of work at the same time.

It will be understood that changes may be made in the details of structure of my feeding machine without departing from the real spirit and purpose of my invention, and it is my intention to cover by my claims, any such modifications or use of equivalents, as may be reasonably included within the scope of my invention.

15 I claim as my invention:

1. A feeding machine having a pair of inclined carrier bars and a pair of chains above the carrier bars for advancing stock thereon, means for vertically adjusting the carrier bars at one end, and means for vertically adjusting the chains at their other ends.

2. In a feeding machine of the class described, means for receiving stock lying flat and advancing it transversely, and means for turning said stock on edge and advancing it longitudinally to either of two spaced operative devices.

3. In a feeding machine, means for receiving and carrying stock, a pair of stock carrying devices spaced from each other, and means for turning the stock received from said first means and discharging it upon either of said stock carrying devices.

4. In a feeding machine, means for receiving and carrying stock, a pair of stock carrying devices spaced from each other, and means for turning the stock received from said first means and discharging it upon either of said stock carrying devices in position standing on edge.

5. In a feeding machine, means for receiving and advancing stock, a pair of spaced troughs, conveying means in said troughs, and means for receiving stock from said first means, turning it on edge, and discharging it into either of said troughs.

6. In a feeding machine, a multiple-sided revolving reel, stock advancing devices on opposite sides of said reel, means for feeding stock to the reel, and means for rotating the reel in either direction for discharging

stock upon either of said stock advancing devices.

7. In a feeding machine, a multiple-sided reel, means for feeding stock to said reel, 55 troughs on the opposite sides of said reel, means for rotating said reel in either direction for discharging stock into either of said troughs, and means for advancing stock lengthwise of the troughs.

8. In a feeding machine, a pair of spaced troughs, means for advancing stock in said troughs, and means for selectively feeding stock to either of said troughs from a source of supply.

65 9. In a feeding machine, a pair of stock advancing devices spaced laterally from each other, a stock carrying mechanism, and means interposed between said stock carrying mechanism and said stock advancing devices for selectively carrying the stock from the stock carrying mechanism to either of the stock advancing devices.

70 10. In a feeding machine, spaced pairs of feed rollers, a stock carrying mechanism, and means for selectively carrying stock from the stock feeding mechanism to either pair of rollers.

75 11. In a feeding machine, a stock carrying mechanism, spaced pairs of feed rollers, 80 devices for advancing stock to the respective pairs of feed rollers, and means interposed between said last devices and the stock carrying mechanism, whereby stock may be transferred selectively from the stock carrying mechanism to either of said advancing devices.

85 12. In a feeding machine, a trough, a conveyor chain traveling on the bottom of the trough part of the length thereof, and feed 90 rollers for taking stock from said chain, advancing it and pressing it against said bottom.

95 13. In a feeding machine, a trough, a conveyor chain traveling on the bottom of the trough part of the length thereof, and feed rollers for taking stock from said chain, advancing it and pressing it against said bottom, said rollers having yielding relative movement.

100 Des Moines, Iowa, April 15, 1924.

SERN MADSEN.
